STRIKER BAR SUSPENSION FOR SELECTIVE
PUNCH DEVICE

Earl E. Masterson, Hickory Lane, Weston, Conn.,
assignor to Sperry Rand Corporation, New York, N.Y.,
a corporation of Delaware

Filed Apr. 10, 1962, Ser. No. 186,393
13 Claims. (Cl. 234—119)

This invention relates generally to machinery for handling data-tabulating cards, and in particular to an improved card-punching mechanism.

Conventional tabulating cards are widely used in a variety of data-processing applications. In many of these high speed is a very important objective, both for reasons of economics, in view of the high cost of data-processing machine time, and for the sake of compatibility with the great speeds attainable by electronic equipment. The latter need is seen, for example, in the case of a card-handling machine such as a summary punch used in an on-line relationship with an electronic computer, which means that the speed of the entire system is limited to that of the lowest component, usually a mechanical unit such as the card-handling machine. Consequently, it is desirable to design card-handling machinery which is capable of operating at high speeds. But such high speed operation creates certain problems, for example the wear which occurs where there is sliding contact between bearing parts moving very rapidly in accordance with high speed data-processing requirements. Thus, as speeds go up problems of lubrication are accentuated, and the length of time that the machine can operate before such bearing parts require replacement or adjustment is sharply reduced, because the machines perform more operating cycles per unit time, and because the amount of wear per cycle increases with higher operating speeds.

Information is entered on tabulating cards by coded combinations of holes punched in the cards. Machinery in which the present invention may be used is designed to perform this punching operation. Typically such card-punching machinery employs a line of punching tools, one such tool for each of the hole locations in a line extending along the width or length dimension of the card. All the punching tools of the line are actuated by a single striker bar which reciprocates at a distance therefrom, and a punching tool selection mechanism is interposed between the striker bar and the line of punching tools to select which of the punching tools shall be actuated and which shall be idle on each particular actuating stroke of the striker bar.

Regardless of which particular punching tools, if any, are actuated on any given stroke, the striker bar keeps reciprocating very rapidly so as to provide a drive which is continuously available whenever a particular combination of punching tools is selected for actuation. Tabulating cards are fed past the operating location of the punching tools at a rather high rate, and each of, for example, twelve rows of holes on each card are punched in rapid succession. In high speed data-processing this operation may have to be repeated at punching speeds of the order of 75 rows per second. This means that the punching mechanism must be capable of 75 punching operations per second; therefore the striker bar must reciprocate at a rate of 75 cycles per second throughout operation of the card-punching machine, whether or not cards are actually being punched at any given moment.

In the past, the art has resorted to sliding friction bearings to mount the striker bar and its associated members for high speed reciprocation. In U.S. Patent No. 3,017,077 of January 16, 1962, for example, the carriage for the reciprocating punch-actuating bar is slidably reciprocated in a cylindrical guide. Such a guide may make

2

use of the known friction-reducing properties of sintered oil-impregnated materials such as Oilite for such applications. In spite of such expedients, during high speed operation such structures wear and after a time they require replacement or adjustment.

Accordingly, it is an object of this invention to provide a striker bar mounting which alleviates the problem of wear. More particularly, this invention aims to provide a mechanism of this type which completely eliminates sliding friction in the suspension of the reciprocating striker bar. Another object is to provide a striker bar suspension which is inexpensive to manufacture.

An illustrative example of a punching mechanism embodying this invention, and exhibiting these and other advantageous features, comprises apparatus formed with a cutting surface and including actuating means effective in response to movement in a selected direction to drive the cutting surface operatively against the material to be punched. Then there is provided at least one flexible member supporting the actuating means, and being sufficiently bendable to permit the required movement of the actuating means.

The device of which the foregoing is a brief summary, may be more fully appreciated by reference to the following detailed description, when read in conjunction with the accompanying drawings, which are as follows:

FIGS. IA through C are a sequence of side elevational views, with parts broken away, sectioned, or removed for clarity of illustration, showing successive stages in the operation of a card-punching mechanism with which the present invention may be employed, with FIGS. IB and C illustrating a striker bar suspension in accordance with this invention;

FIG. ID is a front elevational view, also with parts broken away, sectioned, and omitted, of the mechanism of FIGS. IA through C;

FIG. IE is an enlarged detail of FIG. ID;

And FIG. II is a side elevational view of an alternative embodiment of a striker bar suspension in accordance with this invention.

Referring specifically to the drawings, FIG. IA illustrates a card-punching mechanism of the type which provides a typical environment for the reciprocating suspension of this invention. A punching tool 10, the upper part of which is seen in FIG. IA, is vertically oriented and is mounted, in a manner which will subsequently be discussed, for a vertical movement in which it is driven downwardly against the material to be punched, e.g. a tabulating card, and is subsequently pulled upwardly to extract it from the punched hole.

The downward impetus is applied to the punching tool 10 by a striker bar 12 which reciprocates vertically, as indicated by arrows A. The punching tool 10 would generally be one of, for example, up to eighty such punching tools arranged in a row extending perpendicularly to the plane of FIG. IA. The reciprocating striker bar 12 which is seen in section in FIG. IA, also extends perpendicularly to the plane of that figure and parallel to the row of punching tools 10, so as to be able to actuate all of the eighty individual punching tools in the row. The full length of the striker bar 12 is seen in FIG. ID.

In order to select which of the punching tools 10 are to be actuated on any given operating stroke of the striker bar 12, there are provided selector mechanisms generally designated 14, each interposed between the striker bar 12 and the respective punching tools 10. Each selector mechanism 14 includes a mounting plate 16, and an interposer 18, rocking lever 20, bell crank 22, and cushioning lever 24 mounted on the face of the mounting plate 16. All these members are stamped from sheet metal to make them sufficiently flat for the selector mechanism 14 to be readily accommodated within the thickness (in a

direction perpendicular to the plane of FIG. IA) of the single punching tool 10 operated thereby. FIG. ID illustrates this by showing the way in which the assemblies of the interposers 18 and mounting plates 16 of each punching tool 10 are arranged along the length of the striker bar 12.

Each interposer 18 can be pivoted between one position wherein it is interposed between the striker bar 12 and its punching tool 10 to transmit the motion of the former to the latter, and another position (seen in FIG. IA) wherein it does not so transmit this motion. The interposer 18 is pivotally nested within a recess 20a formed in the rocking lever 20 which rests atop the punching tool 10 and has its right-hand end pivotally connected by means of a pin 30 to the mounting plate 16. A tension spring 32 is connected between the left hand end of the rocking lever 20 and the interposer 18, to bias the latter for counterclockwise rotation toward a position wherein it is struck by the striker bar 12 to transmit the motion thereof to the punching tool 10. However, the interposer 18 is prevented from so moving by the bell crank 22, the mid-section of which is pivotally connected to the mounting plate 16 by a pin 36. A latching arm 22a of the bell crank 22 engages a latching tail 18a of the interposer 18 to hold the latter in the position illustrated in FIG. IA, wherein its upper end is rotated away from the striker bar 12 so as not to be struck thereby and thus not to transmit the motion of the striker bar to the punching tool 10.

FIG. IB shows the interposer 18 in position to permit the striker bar 12 to drive the punching tool 10. As the striker bar 12 is on its upward stroke, an armature arm 22b of the bell crank 22 is attracted upwardly, as indicated by arrow C, by a solenoid 40 which is accommodated within a cut-out 16a formed in the mounting plate 16 (see FIG. IA), and which has just been energized. This rotates the bell crank 22 counterclockwise about its pivot pin 36 to move the latching arm 22a thereof out of latching engagement with the interposer tail 18a, thus permitting the upper part of the interposer 18 to rotate counterclockwise toward the striker bar 12 under the urging of the tension spring 32, as indicated by arrow D.

When the armature arm 22b is fully attracted by the solenoid 40 and the upper part of the interposer 18 has fully rotated under the influence of the tension spring 32, a striking surface 18b thereof is directly below the striker bar 12, which has now descended as indicated by arrow E. A limiting head 18c at the upper end of the interposer 18 hits against the side of the descending striker bar 12 to limit the counterclockwise rotation of the interposer 18 once the latter has reached this position, illustrated in FIG. IB. FIG. ID permits a ready comparison of interposers 18₁ which are in this position preparatory to actuating their respective punching tools 10, and other interposers 18₂ which remain in the punch-idling position.

As the striker bar 12 descends against the striking surface 18b of the interposer 18, it drives the latter downwardly against the rocking lever 20, which in turn pivots counterclockwise about its pin 30 to exert a downward driving force against the top of the punching tool 10. (The fact that the interposer 18 and rocking lever 20 move downwardly together keeps the tension spring 32 tensed therebetween to maintain the biasing force on the interposer.) The punching tool 10 then rides downwardly through a bore formed in a pair of upper and lower punching tool guides 50 and 52 respectively to drive a cutting surface 10a at the lower end thereof through the body of a tabulating card T which has been inserted between upper and lower card guide plates 54 and 56 respectively, and between the upper and lower punching tool guides 50 and 52.

In FIG. IC the striker bar 12 has risen again, as indicated by arrow F, and the punching tool 10 is being extracted from the hole which it has just punched in the

tabulating card T. This extraction is accomplished by a stripper bail 60 which consists of a pair of actuating arms 62, one of which is seen in the drawings, between which is connected a cross-bar 64, seen in section in FIGS. IA-C, extending perpendicularly to the plane of these figures and parallel to the row of punching tools 10. The cross-bar 64 is formed with a tongue 64a which projects into notch 10b formed in each of the punching tools 10. Each such notch 10b has a large enough vertical dimension so that whenever the particular punching tool 10 is not being actuated the tongue 64a rides idly therein as the stripper bail 60 oscillates vertically as indicated by arrows G of FIG. IA, H of FIG. IB, and I of FIG. IC, which it does under the influence of a conventional cam drive (not shown). However, when a particular punching tool 10 has been actuated downwardly to perforate the tabulating card T, then on the next upward cycle of the stripper bail 60 (arrow I in FIG. IC) the tongue 64a engages the upper wall of the notch 10b to raise the punching tool 10. This not only extracts the punching tool 10 from the hole in the tabulating card T, but also causes the punching tool 10 to push upwardly and thereby rotate the rocking lever 20 clockwise about its pin 30 to its original position. The interposer 18, nested in the recess 20a of the rocking lever 20, is also moved upwardly therewith. By this stage in the cycle the solenoid 40 has been de-energized, releasing the armature arm 22b of the bell crank 22 and allowing the latter to be rotated clockwise, as indicated by arrow L, by a compression spring 70 which is received within the solenoid 40 and which acts against the armature arm 22b. This moves the latching arm 22a into position once again to make latching engagement with the tail 18a of the interposer 18 as the latter moves upwardly. As a result of the torque exerted on the interposer 18 by the downward force of the latching arm 22a and the upward thrust of the rocking lever 20, the upper end of the interposer is rotated clockwise, as indicated by arrow M, away from the striker bar 12. At this point the selector mechanism 14 is now returned to its initial position of FIG. IA, and is ready to start a new operating cycle.

In order to assure that the bell crank latching arm 22a comes to rest in the proper place for engaging the interposer tail 18a, there is provided a stop member 72 which is secured to the mounting plate 16 (FIG. IA) by a screw 74. The stop 72 is eccentric with respect to the screw 74 so that it can be adjusted by rotation thereabout. It will be appreciated that as the bell crank 22 is driven back to its initial position by the compression spring 70, the latching arm 22a strikes the stop 72 to limit the return motion of the bell crank 22. In order to prevent the latching arm 22a from thereupon rebounding off the stop 72 and thus being out of position to make latching engagement with the interposer tail 18a at the proper time, there is provided the cushioning lever 24 which is pivotally connected to the mounting plate 16 by means of a pin 76. A short arm 24a of this cushioning lever 24 is connected to a tension spring 78 which is anchored against a portion of the fixed frame 80 of this card-punching machine. This urges the longer arm of the cushioning lever 24 counterclockwise so that a hooked abutment 24b thereof is biased toward the bell crank latching arm 22a. The hooked abutment 24b is long enough to protrude past the stop member 72, but normally the action of the compression spring 70 overrides that of the tension spring 78 so that the latching arm 22a rests against the stop 72, thus holding the cushioning lever 24 away from the stop as seen in FIG. IA. However, as seen in FIG. IB, when the bell crank 22 has been attracted by the solenoid 40 the tension spring 78 then rotates the cushioning lever 24 against the stop 72 so that the hooked abutment 24b thereof protrudes into the return path of the latching arm 22a. Upon its return, the latching arm 22a then strikes the hooked abutment 24b and drives the cushioning lever 24 back from the stop 72. In order to do this it must tense

the spring 78, which thus provides a cushioning action allowing the latching arm 22a to strike the stop 72 more gently so as not to rebound therefrom.

As seen in FIGS. IB, C, and D, in accordance with this invention the striker bar 12 is mounted on a carriage 100 by means of a horizontal extension 12a which is secured thereto by bolts such as 102. The carriage 100 is secured at either end to a pair of pillars 104 by means of bolts 106. These pillars 104 in turn are supported upon one end of four flexible members 108 in the form of flexure springs made of leaf-shaped strips of sheet material. The other ends of the flexure springs 108 are secured to another pair of pillars 110, only one of which is visible in the drawings, which in turn are secured by means of bolts such as 112 to a depending part of the fixed frame 80 of the card-punching machine. The ends of the flexure springs 108 are clamped against the pillars 104 and 110 by means of clamping bars 114 which clasp the flexure springs against the pillars 104 and 110 and are secured thereto by bolts such as 116.

In FIG. IB it is seen that when the assembly of the pillars 104, carriage 100, and striker bar 12 is driven downwardly through its punch-actuating stroke, the flexure springs 108 bend in the manner illustrated, thus providing a suspension which allows these members the required freedom of vertical movement. Thereafter the flexure springs 108 spring back to the position of FIG. IC. The flat shape of the springs 108 is adapted to permit this motion, which is perpendicular to the planes that these springs define, yet it offers sufficient rigidity parallel to those planes to restrain motion in any direction other than perpendicular thereto. It will be appreciated that the springs 108 of this suspension are easily and inexpensively stamped from sheet materials and their tolerances are not as critical as those of conventional cylindrical guides. They are also free from rubbing friction, and therefore they need no lubrication, yet provide a low-wear mechanism well adapted to the high operating speeds required of tabulating card equipment.

However, in order to lengthen the life of the flexure springs 108 it is advisable to prevent the bending stresses exerted on them from being concentrated at the places where they emerge from between the pillars 104 and 110 and the clamping bars 114. This is done by making the curvatures of these clamping bars and pillars at the locations 118 quite gentle, as shown in FIGS. IB, C, and D. It is also advisable to minimize the effects of the bending stresses on the springs 108 by fabricating them of materials such as steel, beryllium copper, or Phosphor bronze, and by choosing their dimensions such that they operate well within the static and dynamic stress and fatigue limits of the material. Another design consideration to be borne in mind is the fact that in bending to permit vertical reciprocation, the springs 108 introduce a small horizontal component into the motion of the striker bar assembly (carriage 100 and striker bar 12). However this is easily compensated for by making the horizontal extent of the interposer striking surface 18b large enough to be under the striker bar 12 at all relevant phases of its vertical reciprocation. The use of springs 108 at both the top and bottom of the pillars 104 and 110 results in a kind of rectangular linkage which keeps the carriage 100 in a vertical attitude so that the problem of horizontal motion is not accentuated by tilting of the carriage.

The drive for the reciprocating motion of the striker bar assembly is seen in FIGS. IC and D. The carriage 100 oscillates vertically within a recess 80a formed in an overhanging part of the fixed machine frame 80. The horizontal dimension of this recess 80a as seen in section in FIG. IC is made large enough to provide clearance for the small horizontal component of the motion of the carriage 100, mentioned above. As seen in FIG. ID, a drive shaft 130 extends through the illustrated portion of the frame 80 and is journaled thereon by a pair of bearings 132. On this shaft 130 are affixed a pair of cams

134, the section of the shaft between the two cams being formed with an eccentric portion 130a to counter the dynamic imbalance of the cams. These cams 134 work against cam follower rollers 136 rotatably mounted upon stub shafts 138 within slots 100a formed in the carriage 100, to drive the carriage and striker bar 12 downwardly through their punch actuating stroke.

In order to return the carriage 100 at the end of each such punch-actuating stroke, there are provided a number of return springs 140, one of which is shown in the drawing. One such spring is mounted in each of five openings 100b formed in the carriage 100. These return springs 140 act in compression upwardly against the upper surface of their respective openings 100b to return the carriage 100 upwardly after each driving cycle of the cams 134. At their lower ends the springs 140 act downwardly against U-shaped spring seats 142. As seen in FIG. IC these spring seats 142 have front and rear horizontal lugs 142a and 142b which are secured by means of bolts such as 144 to the front and rear undersurfaces 80b and 80c respectively of the overhanging portion of the fixed machine frame 80. The central portions 142c of the U-shaped members 142 extend through the respective openings 100b of the carriage 100 to provide a base against which the return springs 140 act downwardly. Spring-retainer dowels 144 (one of which is shown in FIG. ID) are oriented within each return spring 140 and are secured by means of bolts such as 146 to the central portions 142c of the respective spring seats 142.

In the alternative embodiment of FIG. II, it is seen that the striker bar 12' is again secured by means of a horizontal extension 12a' and bolts such as 102' to the lower end of a carriage 100'. In this embodiment the upper end of the carriage 100' forms a yoke 200 which rotatably receives and is mounted upon a disc 202 eccentrically carried upon a drive shaft (not shown) journaled on the fixed frame 80' of the machine in a fashion similar to the drive shaft 130 in FIG. ID. This eccentric arrangement is the drive which vertically oscillates the carriage 100' and striker bar 12'. A pair of brackets 210, one of which is visible in the drawing, are secured by bolts such as 212 to the fixed machine frame 80', and depend therefrom. In this embodiment only two flexure springs 108' are required for restraining and supporting the lower end of the carriage 100' and striker bar 12', one such spring being visible in the drawing. One end of each of the flexure springs 108' is clamped to the lower end of the bracket 210 by means of a clamping bar 114' and bolts such as 116' in the manner previously described. The other ends of the springs 108' are secured between the carriage 100' and the clamping bar formed by the striker bar horizontal extension 12a'. On members 114' and 12a' the stress-relieving curvatures 118' are again employed. Here again the springs 108' bend vertically in a friction-free manner to allow the striker bar 12' the necessary latitude of vertical movement, while acting to restrain undesired horizontal movement thereof.

The foregoing illustrates preferred ways of practicing this invention; but since there may be countless other specific applications of the same principles, the scope of protection is not limited to any particular examples, but is defined more generally in the appended claims.

The invention claimed is:

1. A mechanism for punching material, comprising:
- I. Apparatus having a cutting tool means formed with a cutting surface;
- II. And including actuating means arranged to provide movement to said cutting tool means in a selected direction operatively against the material;
- III. And further including interposer means arranged to selectively form an operative connection between said cutting tool means and said actuating means;
- IV. And at least one flexible member secured in place and connected to limit displacement of the actuating

- means transversely to the selected direction and being sufficiently bendable to permit such movement thereof in the selected direction.
2. A mechanism for punching material, comprising:
- I. At least one punching tool;
  - II. Means reciprocable in a selected direction to provide movement to said punching tool operatively against the material;
  - III. And further including interposer means arranged to selectively form an operative connection between said punching tool and said reciprocable means;
  - IV. And at least one flexible member secured in place and connected to limit displacement of the reciprocable means transversely to the selected direction and being sufficiently bendable to permit such reciprocation thereof in the selected direction.
- 15
3. A mechanism for punching material, comprising:
- I. At least one punching tool;
  - II. Means reciprocable in a selected direction to provide movement to said punching tool operatively against the material;
  - III. And further including interposer means arranged to selectively form an operative connection between said punching tool and said reciprocable means;
  - IV. At least one flexible leaf arranged with its plane substantially perpendicular to the selected direction, secured in place and connected to limit displacement of the reciprocable means transversely to the selected direction and being sufficiently bendable to permit such reciprocation thereof in the selected direction.

25

4. A mechanism for punching material, comprising:

    - I. At least one punching tool;
    - II. Means reciprocable in a selected direction to provide movement to said punching tool operatively against the material;
    - III. And further including interposer means arranged to selectively form an operative connection between said punching tool and said reciprocable means;
    - IV. And at least one flexible member extending in a direction transverse to the selected direction, secured in place and connected to limit displacement of the reciprocable means transversely to the selected direction and being sufficiently bendable to permit such reciprocation thereof in the selected direction.

40

5. A mechanism for punching material, comprising:

      - I. At least one punching tool;
      - II. Means reciprocable in a selected direction to provide movement to said punching tool operatively against the material;
      - III. And further including interposer means arranged to selectively form an operative connection between said punching tool and said reciprocable means;
      - IV. And at least one flexure spring extending in a direction transverse to the selected direction, secured in place and connected to limit displacement of the reciprocable means transversely to the selected direction and being sufficiently bendable to permit such reciprocation thereof in the selected direction.

45

6. A mechanism for punching material, comprising:

        - I. At least one punching tool;
        - II. Means located at a distance from the punching tool and reciprocable in a selected direction to drive the punching tool operatively against the material;
        - III. Interposer means located substantially between the punching tool and the reciprocable means;
        - IV. Means mounting the interposer means for movement between a position effective to transmit motion from the reciprocable means to the punching tool, and a position effective to idle the punching tool;
        - V. And at least one flexure spring extending in a direction transverse to the selected direction, secured in place and connected to limit displacement of the reciprocable means transversely to the selected direction and being sufficiently bendable to permit such reciprocation thereof in the selected direction.

55

70

75

7. A mechanism for punching material, comprising:
- I. A plurality of punching tools arranged in a line extending in a first direction;
  - II. Means which—
- A. Include a striker bar extending in the first direction and located at a distance from the punching tools;
  - B. Are reciprocable in a second direction for the striker bar to drive the punching tools operatively against the material;
  - III. A plurality of interposer means each located substantially between a respective one of the punching tools and the striker bar;
  - IV. Means mounting each of the interposer means for movement between a position effective to transmit motion from the striker bar to its respective punching tool, and a position effective to idle its respective punching tool, whereby to select the desired punching tools for operation;
  - V. And at least one flexure spring extending in a direction transverse to the second direction, secured in place and connected to limit displacement of the reciprocable means transversely to the second direction and being sufficiently bendable to permit such reciprocation thereof in the second direction.
8. A mechanism for punching material, comprising:
- I. A plurality of punching tools arranged in a line extending in a first direction;
  - II. Means which—
- A. Have opposite ends with respect to the first direction;
  - B. Include a striker bar extending in the first direction and located at a distance from the punching tools;
  - C. And are reciprocable in a second direction for the striker bar to drive the punching tools operatively against the material;
  - III. A plurality of interposer means each located substantially between a respective one of the punching tools and the striker bar;
  - IV. Means mounting each of the interposer means for movement between a position effective to transmit motion from the striker bar to its respective punching tool, and a position effective to idle its respective punching tool, whereby to select the desired punching tools for operation;
  - V. And a pair of flexure springs extending in a direction transverse to the second direction, secured in place and connected to the respective opposite ends of the reciprocable means to limit movement thereof transversely to the second direction and being sufficiently bendable to permit such reciprocation thereof in the second direction.
9. A mechanism for punching material, comprising:
- I. A supporting frame;
  - II. At least one punching tool;
  - III. Means for actuating the punching tool including—
- A. A carriage reciprocable in a selected direction,
  - B. And a member on the carriage reciprocable therewith to drive the punching tool operatively against the material;
  - IV. Means operatively connected between the frame and the carriage to reciprocate the carriage in the selected direction whereby to move the drive member through its punch-actuating reciprocation;
  - V. And at least one flexure spring secured to the frame and extending therefrom in a direction transverse to the selected direction;
  - VI. The extending part of the flexure spring being connected to limit movement of the carriage transversely to the selected direction and being sufficiently bendable to permit such reciprocation thereof in the selected direction.
10. A mechanism for punching material, comprising:
- I. A supporting frame;

- II. At least one punching tool;
- III. Means for actuating the punching tool including—
  - A. A carriage reciprocable in a selected direction, and having opposite ends with respect to a direction transverse thereto,
  - B. Spring-holders at the opposite ends of the carriage,
  - C. And a member on the carriage reciprocable therewith to drive the punching tool operatively against the material;
- IV. Means operatively connected between the frame and the carriage to reciprocate the carriage in the selected direction whereby to move the drive member through its punch-actuating reciprocation;
- V. And pairs of flexure springs secured to the frame and extending therefrom in a direction transverse to the selected direction;
- VI. The extending parts of the pairs of flexure springs being connected to the spring-holders at the respective opposite ends of the carriage to limit movement thereof transversely to the selected direction and being sufficiently bendable to permit such reciprocation thereof in the selected direction.
- 11. A mechanism for punching material, comprising:
  - I. A supporting frame;
  - II. At least one punching tool;
  - III. Means for actuating the punching tool including—
    - A. A carriage reciprocable in a selected direction,
    - B. And a member on the carriage reciprocable therewith to drive the punching tool operatively against the material;
  - IV. Means operatively connected between the frame and the carriage to move the carriage and drive member through a punch-actuating stroke;
  - V. At least one recess formed in the carriage;
  - VI. A return spring received within the recess and operable against the carriage for returning the carriage and drive member to their original positions after each such punch-actuating stroke;
  - VII. A spring seat secured to the frame and protruding into the recess and engaging the return spring whereby to provide a base for the return action thereof;
  - VIII. And at least one flexure spring secured to the frame and extending therefrom in a direction transverse to the selected direction;
  - IX. The extending part of the flexure spring being connected to limit movement of the carriage transversely to the selected direction and being sufficiently bendable to permit such reciprocation thereof in the selected direction.

- 12. A mechanism for punching material, comprising:
  - I. A supporting frame;
  - II. At least one punching tool;
  - III. Means for actuating the punching tool including—
    - A. A carriage having opposite ends with respect to a selected direction and reciprocable in that direction.
    - B. And a member on a first end of the carriage reciprocable therewith to drive the punching tool operatively against the material;
  - IV. Means operatively connected between the frame and a second end of the carriage to move the carriage and drive member through a punch-actuating stroke;
  - V. And at least one flexure spring secured to the frame and extending therefrom in a direction transverse to the selected direction;
  - VI. The extending part of the flexure spring being connected to limit movement of the first end of the carriage transversely to the selected direction and being sufficiently bendable to permit such reciprocation thereof in the selected direction.
- 13. A mechanism for punching material, comprising:
  - I. A supporting frame;
  - II. At least one punching tool;
  - III. Means for actuating the punching tool including—
    - A. A vertically reciprocable carriage having upper and lower portions, and opposite ends with respect to a horizontal direction,
    - B. And a member on the lower portion of the carriage reciprocable therewith to drive the punching tool operatively against the material;
  - IV. Means operatively connected between the frame and the upper portion of the carriage to move the carriage and drive member through a punch-actuating stroke;
  - V. And a pair of flexure springs secured to the frame and extending horizontally therefrom;
  - VI. The extending parts of the flexure springs being connected to the respective opposite ends of the lower portion of the carriage to limit horizontal movement thereof and being sufficiently bendable to permit such vertical reciprocation thereof.
